TIGHT LOCK CAR COUPLER

Herbert E. Van Dorn, Chicago, Ill., assignor to
The Dornvan Corporation, a corporation of Illinois

Application April 15, 1946, Serial No. 662,255

8 Claims. (Cl. 213—77)

1

In my prior Patent 2,209,365, there is disclosed a novel means for mounting and controlling the swinging locking dog or block of a car coupler of the tight-lock type; the dog in one coupler being automatically tightened against the hook-like nose of a companion coupler and automatically adjusting itself to compensate for wear; and the pressure between the nose and the cooperating dog being released, for uncoupling, by shifting the dog bodily away from the nose before swinging it into its unlocking position.

The object of the present invention is to simplify and improve the construction and operation of the car coupler of the aforesaid patent.

The various features of novelty whereby the present invention is characterized will herein-after be pointed out with particularity in the appended claims; but, for a full understanding of the invention and of its objects and advantages, reference may be had to the following detailed description taken in connection with the accompanying drawings, wherein:

Figure 1 is a top plan view of a car coupler embodying the present invention; Fig. 2 is a front view of the same; Fig. 3 is a section on a somewhat larger scale, on a horizontal plane, of a like coupler turned end for end with respect to the coupler of Fig. 1, so as to adapt it to interlock with the latter, the parts being in the normal idle or uncoupled positions; Fig. 4 is a view similar to Fig. 3, showing only a fragment of the coupler, together with the nose of a second coupler that is tightly coupled thereto; Fig. 5 is a view similar to Fig. 4, showing the locking dog latched in its release position, so that the two couplers may pull apart from each other; Fig. 6 is a view similar to Figs. 4 and 5, showing the parts in the positions occupied at the moment that the latch for the dog is being tripped by the retreating nose of the second coupler, and parts of the upper flange on the locking dog and the piston rod for turning it in one direction being broken away; Figs. 7 and 8 are sections on lines 7—7 and 8—8 of Fig. 4, respectively, the locking dog and its immediate operating means being shown in elevation; Fig. 9 is a view of the immediate actuator for the dog removed from the coupler, with the hinge pin for the same and the dog in the same position relative to the actuator that it has in the assembled coupler; and Fig. 10 is a top plan view of the locking dog, removed from the coupler.

In the drawings there is illustrated a hollow coupler head 1 which has at the front end, on one side of the longitudinal center, a hook-like nose 2 provided on one side with a flat, laterally inclined front face 3 adapted to engage with a correspondingly inclined face 4 in a companion coupler; face 4 being on the opposite side of the longitudinal center of the head and being wholly

5 in the interior of the latter. Within the head, directly behind the face 4, and in registration with an opening or window 5 in such face, is a locking dog 6 in the form of a heavy steel block. The face 3 of the nose contains a window 7 so placed that it creates a face 8 that is on the back side of the nose parallel to the longitudinal axis of the coupler.

10 The locking dog is mounted on one end on a hinge pin 9 which in turn extends through and is journaled in two eccentric bearing blocks 10 and 11 rotatably supported in the top and bottom walls of the coupler head. Broadly speaking, parts 1—11 are old, being found in the construction disclosed in my aforesaid patent. The upper eccentric 10 has at the bottom a flange-like part 12 in the form of a wide, flat radial arm of considerable length. There is a similar flange or arm 12 on the upper end of the lower eccentric; 15 the two eccentrics with their arms being alike; one being simply turned up side down relative to each other. In the outer end of each of these arms is a wide, deep notch 14. The height of the locking block is less than the distance between the eccentrics, leaving space between each eccentric and the block for one of the arms of a two-armed actuator; this actuator comprising a short, 20 heavy vertical bar 15 to which are fixed flat, paddle-like radial arms 16 provided near their free ends with holes through which the shaft 9 extends. The parts are so proportioned that when they are assembled the bar 15 is seated in the notches 14 in the arms on the eccentrics. Therefore, when the bar is swung about the hinge pin, 25 the eccentrics turn with it. The locking dog also has flanges or flat, radial arms, 17 and 18, projecting therefrom, one above the other, at the top and bottom of the dog. The arms or flanges on the dog are provided with 30 notches 19 in their outer ends; these notches being wider and usually a little deeper than the notches 14 and being so positioned that the bar element 15 of the actuator extends through the same. Except that there is a lost motion between 35 them, due to the difference between the widths of notches 14 and 19, the locking dog and the actuator turn together; the effect being in general 40 the same as in the construction disclosed in the aforesaid patent.

45 The bar 15 of the actuator has a rigid, heavy lever arm 20 extending radially therefrom out through an opening 21 in the side wall of the coupler head. There it is connected to a powerful device tending constantly to swing it in the direction to cause the locking dog to move out 50 through window 5 in the front of the coupler, as in Fig. 3. This device comprises a rod 22 connected at its front end to the arm 20 by a hinge pin 24 and extending rearward into a cylindrical

casing 25 which contains a long powerful coil spring or springs 26 surrounding and coaxial with the rod. On the rear end of the rod is fixed a disc 27 that engages with the rear end of the spring means.

In order to move the locking dog in the opposite direction from that in which the spring tends constantly to move it, I provide a pneumatic actuator comprising a cylinder 28 secured within the interior of the coupler head, on the nose side of the head; the axis of the cylinder being horizontal and extending diagonally across the interior of the coupler head to intersect the vertical bar member 15 of the immediate operating means for the eccentrics and the locking dog. In this cylinder is a piston 29 to which there is fastened a piston rod 30. Within this cylinder, surrounding the piston rod, is a compression spring 31 that engages the piston and normally holds it against the outer end or head of the cylinder. Normally, with the piston at the outer end of its stroke, the piston rod or plunger protrudes so far as to be near the bar 15 of the actuator when the parts are in their normal, uncoupled positions. Upon admitting air under pressure into the outer end of the cylinder, through an inlet 32, the piston is forced toward the inner end of the cylinder, the rod or plunger strikes bar 15, and the locking dog is swung back through window 5 into release position to permit automatic uncoupling.

A suitable latch must be provided to hold the locking dog in its release position until the uncoupling is completed. For this purpose I mount in the bottom of the coupler head, in the space behind the locking dog, a horizontally swinging latch 34. The rear end of the latch is anchored to the coupler head by a vertical hinge pin 35 and has at its forward end a lug 36 to engage with the side of bar 15 when the locking dog has been moved into release position; the latch serving as a strut to prevent the bar from being moved by the force constantly exerted against it by spring device 26. There is a compression spring 37 engaged with the rear edge of the latch at an intermediate point in the length thereof; this spring tending constantly to hold the latch in its latching position.

The latch must be tripped automatically in uncoupling, so as to leave the coupler in condition to couple automatically at some subsequent time. This is done by the locking dog, activated by a part of the opposing coupler. It will be seen that the locking dog has a large cam 38 projecting from its forward face, the same being a lug that is triangular as viewed from above. This cam lies, inward from the cam face 6^a of the locking dog and, therefore, does not in any way interfere with or aid in maintaining a tight lock between the couplers. The parts are so proportioned that when the locking dog is latched in its release position, as in Fig. 5, the cam 38 extends out into the path of the nose of the opposed coupler as it slides along the inclined face 4 during uncoupling. Consequently the retreating nose engages the cam and forces it back behind the plane of face 4, as in Fig. 6. This is the movement of the locking dog that is utilized to trip the latch; the tripping being done by direct contact between the locking dog and the latch. It will be seen that the latch has on top thereof, along its front edge and about midway between its ends, a lug 39 which stands clear of the dog when the dog is brought into its release position. However, when the dog is pushed back, during uncoupling, as just

explained, it strikes the lug and pushes the forward end of the latch clear of bar 15.

In order to limit the forward swinging movement of the locking dog, when released as just explained, it is provided with an upwardly projecting lug 40 which, as best shown in Fig. 7, strikes against a ledge 41 on the top wall of the coupler head when the parts are in normal uncoupled positions.

The hinge pin 9 for the locking dog may conveniently be inserted from above the coupler head, through the bore 42 in which the upper eccentric is seated. The top of this bore is then closed by a casting 43 held in place by two screws 44, as best shown in Figs. 7 and 8; a pad of felt 45, capable of absorbing a considerable amount of oil, being interposed between this casting and the tops of the shaft and eccentric. Also, for convenience in manufacture, the bore 46 in the bottom wall to receive the lower eccentric terminates in a smaller bore section 46^a, somewhat larger in diameter than pin 9. A cylindrical plug 47, provided around the top with a flange 48, is pressed into bore section 46^a, from above, to form a support for the lower end of the pin.

It may sometimes be desired to uncouple manually from the ground. I have therefore provided the outer free end of arm 20 of the locking dog actuator with a socket 49 into which a heavy rod or the like may be inserted to permit the locking dog to be swung back into release position without making use of the air cylinder.

When air connections between cars are to be effected by the act of making a mechanical coupling between the cars, suitable air terminal devices 50 may be bolted in place within the coupler heads about midway between and parallel with the forward, inclined faces 3 and 4; whereby the air terminals in opposing couplers are brought together by movements which result in axial alignment thereof when they meet. In the arrangement shown, the cylinder 28 and the air coupling unit 50 are provided with large, heavy ears, 51 and 52, respectively, which overlap each other and rest on a boss 54 on the coupler head casting, within the coupler head; a screw 55 extending through both of these ears and into the boss. Cylinder 28 may be further secured by another flange 56 and screw 57 and the air coupling unit by a flange 58 and screw 59; these flanges being on the outside of a side wall of the coupler head, and the screws entering this wall.

The operation of the coupler will be briefly summarized. With the parts of two couplers in the uncoupled or idle positions illustrated in Fig. 3: when the couplers come together, the nose in each pushes the locking dog of the other back out of its idle position as indicated in Fig. 6, which may be said to represent a stage in either a coupling or an uncoupling operation. It will be noted that in Fig. 6 the bar 15 has not been pushed back far enough to permit the latch to drop in front of the same when the nose of the opposing coupler slides past the locking dog. Therefore the spring device 26, which was compressed when the dog was pressed back by the opposing coupler, goes into action and drives the dog into the position shown in Fig. 4, or as much farther as may be necessary to wedge the two heads into a rigid whole.

When it is desired to uncouple, air is admitted into cylinder 28, or the lever arm 20 is manually operated, to turn the dog back into the position which it occupies in Fig. 5; the latch dropping into latching position with the cam 38 on the dog pro-

jecting into the path which the nose of the opposing coupler must follow when the couplers begin to separate. When such separating movement between the coupler heads begins, the nose of the opposing coupler engages cam 38 and brings about the conditions illustrated in Fig. 6. As previously pointed out, although the latch has now been tripped, it cannot snap back to hold the dog from swinging out to the uncoupled position of Fig. 3 when the couplers are completely separated; this being due to the fact that the dog must be swung back farther to bring it into its release position for uncoupling than is necessary for the purpose of tripping the catch or of swinging the dog out of the way of the nose of a second coupler during automatic coupling.

Every swinging movement of the bar 15 in the clockwise direction, as viewed in Figs. 3-6, results in a bodily lengthwise shifting movement of the dog, due to turning of the eccentrics. Therefore, because of the large angle through which the eccentrics in the present construction are caused to turn, the capacity of the coupler automatically to compensate for wear is very great and increased life of the coupler is assured.

It will further be seen that by using a very simple latch and allowing the locking dog to act directly on the same, to unlatch, not only is the initial cost kept low, but there is practically no maintenance cost in connection with the unlatching means.

I claim:

1. The combination with the swinging locking dog in a tight lock car coupler movable from an idle position through a locking position and past a release position, of an actuating member connected with the dog so as to swing therewith while having a limited angular movement relative thereto about their common axis, of a spring tending constantly to move the actuator in the direction to carry the dog to and through the locking position and into its forward idle position, means to turn the actuator in the opposite direction to bring the dog into its release position, a latch adapted to engage the actuator in a manner to prevent movement thereof while the actuator is holding the dog in the release position, and a part on the dog in position to engage the latch and trip it when the dog is pressed back beyond the release point.

2. The combination as set forth in claim 1, wherein the locking dog has thereon an element that lies in the path of a part of a companion coupler during the separating movements of two couplers and causes the dog to be pushed back beyond its release position and trip the latch.

3. The combination with a car coupler of the tight lock type having a swinging locking dog spring held in a forward idle position and adapted to be pushed back by a second coupler, in the act of coupling and then drop into locking position with respect to the second coupler, and having a device to move the dog from its locking position back to a release position; of an actuator through which both the spring and said device act to move the dog, the actuator being connected to the dog in a manner to provide a small lost motion between the actuator and the dog, a latch in position to engage the actuator when it moves the dog into the release position and thereby lock the dog in that position, the dog having thereon a part in position to engage the latch and trip the same when the dog is pushed back past the release position, and a cam on the front of the dog to be

engaged by a companion coupler both upon the separation and the coupling of the couplers to push the dog back past the release position in coupling.

5. In a car coupler of the tight lock type, a locking dog, a vertical hinge pin extending through one end of the dog, rotatable bearing blocks containing eccentrically disposed openings to receive the ends of the hinge pin, a vertical actuating bar having radial arms extending between the dog and the eccentrics and connected to the hinge pin to permit the bar to swing on the pin, radial arms on the eccentrics and the dog having in their ends notches in which the actuating bar is entered, the notches in the arms on the dog being wider than those in the arms on the eccentrics to provide a lost motion between the actuator and the eccentrics a spring device tending constantly to move the actuating bar in the direction to shift the dog into a forward idle position, a lever arm projecting laterally from the actuating bar to swing it in the direction to bring the dog into a rearward release position, and a latch in position to drop in front of the actuating bar when the latter is holding the dog in the release position.

5. A car coupler as set forth in claim 4, wherein the locking dog has on the front face a cam that projects into the path of a part on a companion coupler when two couplers begin to separate, in uncoupling, and causes the locking dog to be pushed back a little past its release position, and wherein the dog engages the latch during this latter movement and trips it.

35. 6. A car coupler as set forth in claim 4, wherein a power-operated plunger moves into engagement with the lever arm to move it in the direction to set the locking dog in the release position and then retreats to leave the dog free to be moved by the spring mean upon tripping of the latch.

45. 7. A car coupler of the tight lock type comprising a head containing a locking dog swingable from a forward idle position back to and somewhat beyond a release position, a spring pressed actuator connected to the dog so as to have a limited movement relative to the same and tending constantly to move the dog into its idle position, a latch in position to engage the actuator when the latter moves the dog into the release position, a cam on the dog in position to be engaged by a part on a companion coupler during uncoupling and force the dog backward from the release position, and said dog having thereon an element that engages the latch when the dog is so pushed back, in uncoupling, and trips the latch.

55. 8. A car coupler as set forth in claim 7 including an uncoupling member movable from a retracted position into engagement with the actuator to force the latter in the direction to shift the dog into its release position.
